(57) **CLAIM**

The ornamental designs for a portable battery assembly, as shown and described.

DESCRIPTION

FIG. 1 is perspective view of a portable battery assembly, showing my new design.

FIG. 2 is a front elevational view of the portable battery assembly of FIG. 1.

FIG. 3 is a rear elevational view of the portable battery assembly of FIG. 1.

FIG. 4 is a left elevational view of the portable battery assembly of FIG. 1.

FIG. 5 is a right elevational view of the portable battery assembly of FIG. 1.

FIG. 6 is a top plan view of the portable battery assembly of FIG. 1.

FIG. 7 is a bottom plan view of the portable battery assembly of FIG. 1.

FIG. 8 is a perspective view of the portable battery assembly of FIG. 1, showing an auxiliary pack of the portable battery assembly removed from the base of the portable battery assembly.

FIG. 9 is a top plan view of the portable battery assembly of FIG. 1, without the auxiliary pack.

FIG. 10 is a perspective view of an auxiliary pack for a portable battery assembly.

FIG. 11 is a left elevational view of the auxiliary pack of FIG. 10.

FIG. 12 is a right elevational view of the auxiliary pack of FIG. 10.

FIG. 13 is a rear elevational view of the auxiliary pack of FIG. 10.
